COILING APPARATUS

Julius A. Wagner, Cleveland Heights, Ohio, assignor to Western Electric Company, Incorporated, New York, N. Y., a corporation of New York

Application January 11, 1945, Serial No. 572,417

14 Claims. (Cl. 242—82)

1

This invention relates to a coiling apparatus and more particularly to an apparatus for selectively coiling lengths of cordage.

It is an object of the present invention to provide a simple and effective apparatus for coiling lengths of flexible material.

In accordance with one embodiment of the invention, an apparatus is provided for coiling multi-conductor cordage in coils of lengths determined by the distance between points where the conductors extend in loops through the covering on the cordage. In this apparatus, an angularly disposed nozzle rotates above a receptacle having a movable bottom, in such a manner as to lay a coil of cordage on the bottom of the receptacle and mechanism is provided for withdrawing the bottom of the receptacle each time the projecting loops of conductors pass a predetermined point in the apparatus.

A complete understanding of the invention may be had by reference to the following detailed description when considered in conjunction with the accompanying drawings, wherein

Fig. 1 is a fragmentary elevational view, partly in section, of a cordage processing machine and showing the mechanism for coiling cordage and delivering coils, thereof, to a processing machine;

Fig. 2 is a fragmentary vertical sectional view, on an enlarged scale, taken substantially along the line 2—2 of Fig. 1 in the direction of the arrows;

Fig. 3 is an enlarged fragmentary plan sectional view taken substantially along the line 3—3 of Fig. 1 in the direction of the arrows;

Fig. 4 is an irregular plan sectional view taken substantially along the line 4—4 of Fig. 1 in the direction of the arrows, parts being broken away to conserve space;

Fig. 5 is a diagrammatic view of the gearing which cooperates to feed the cordage; and

Fig. 6 is a circuit diagram of a control circuit for the apparatus.

Referring to the drawings, wherein like reference characters designate the same parts throughout the several views, particular reference being first had to Fig. 1 wherein there is shown a turret bearing post 10 which constitutes the main bearing for a turret assembly 11 of a processing machine which may be of the type disclosed in the copending application of R. T. Adams and J. A. Wagner, Serial No. 572,414 filed January 11, 1945. The turret assembly 11 comprises a driving gear 12, adapted to be driven in timed relation to the various operations of the processing machine, and having fixed to it

2

a cord coil supporting table 13. Fixed to the stationary bearing post 10 is an annular support member 14 having suitably attached to it a housing base 15 on which there is in turn mounted a housing 16.

The housing 16 has a motor 17 suitably mounted therein and connected to a gear reducer 18 for driving a pulley 19. The pulley 19 is adapted to drive a belt 20 which in turn drives the driving element 21 of a clutch assembly designated generally by the numeral 22 (Fig. 3). The driving element 21 is freely rotatable on a shaft 23 and may be clutched to the shaft by clutch discs 24 surrounding the shaft 23 and seated in a nest 25 in the driving element 21 when pressure is applied to the discs 24. Pressure may be applied to the discs 24 by a sleeve 26 having a pair of shoulders 27 and 28 formed on it for receiving clutch operating rollers 29 mounted upon opposite arms of a clutch lever 30 when the lever 30 is in one of its operating positions. The shaft 23 is journaled in a bearing block 31 and in a tubular portion 32 of the driving element 21. The clutch lever 30 will apply pressure to brake discs 33 surrounding the shaft 23 and seated in a nest 34 in the bearing block 31 in its other operating position, and thus when the clutch lever 30 is rocked clockwise, from the position shown in Fig. 3, it will cause the driving element 21 to be connected to the shaft 23 and when the clutch lever 30 is rocked to the position shown in Fig. 3, it will brake the shaft 23 against the bearing block 31. The tubular portion 32 of the driving element 21 is journaled in a bearing sleeve 35 attached to the housing 16.

The clutch lever 30 is fixed to a shaft 36 journaled in vertically disposed portions of the housing 16. At its upper end, as shown in Fig. 1, the shaft 36 has a lever 37 fixed to it for normally urging the shaft 36 to rock in a clockwise direction under the action of a contractile spring 38. The spring 38 is mounted in a solenoid housing 39 into which the lever 37 extends and the lever 37 may be moved to rock the shaft counterclockwise as viewed in Fig. 3 by a solenoid coil 40 (Fig. 6) also mounted in the solenoid housing 39. The housing 39 is suitably positioned on the housing 16 and a second solenoid housing 41 is also mounted upon the housing 16. The housing 41 has a solenoid coil 42 mounted in it adapted to actuate a core member 43. The core member 43 has a link 44 attached to it and to a bell crank lever 45 mounted upon a pivot pin 46. The pivot pin 46 is carried by a bracket 47 in which there is slidably mounted a plunger 48 (Fig. 4). Formed

on the left end of the plunger 48, as shown most clearly in Fig. 4, is a double sided rack 49 which is urged to the right (Figs. 1 and 4) by a compression spring 50 seated against a shoulder 51 formed in the bracket 47. The compression spring 50 surrounds the shank of the plunger 48 and, in addition to bearing against shoulder 51, bears against a collar 52 on the plunger 48, thus to urge the plunger 48 into engagement with the vertically extending arm of the bell crank lever 45. Meshing with the rack 49 are a pair of gears 53 and 54 suitably fixed to the upper ends of stud shafts 55 and 56, respectively, which are journaled for rotation in a bearing portion 57 of the bracket 47 and have fixed to their lower ends a pair of levers 58 and 59. Formed integrally with the levers 58 and 59 or suitably attached to them are a pair of closure plates 60 and 61 which cooperate to serve as the bottom of a coil receptacle 62 which comprises, in addition to the closure plates 60 and 61, a frusto conically shaped wall member 63 which is connected to the bearing portion 57 of the bracket 47 by web members 64-64. The abutting edges of the closure members 60 and 61, as shown most clearly in Fig. 2, have angle members 65-65 attached to them for cooperating with the bottom surfaces of the closure members to support soft rubber gaskets 66-66.

The housing 16 is irregularly shaped, as shown in Fig. 3, and has a gear case 75 mounted on it which serves to enclose the driving gears for the mechanism which feeds coils into the coil receptacle 62. These driving gears comprise a gear 76 (Figs. 3 and 5) fixed to the shaft 23 and meshing with a pinion 77 mounted upon a stud shaft 18 suitably journaled in the housing 16 and having keyed thereto a pinion 79 and a worm gear 80. The pinion 79 meshes with and drives a gear 81 fixed to a stud shaft 82 and carrying a spur gear 83 which in turn meshes with a spur gear 84 on a stud shaft 85. The stud shafts 82 and 85 have keyed to them a pair of feed rollers 86 and 87, respectively, having soft rubber tires 88 and 89, respectively, for engaging and feeding cordage 90. The shafts 82 and 85 are mounted in bearing blocks 91 and 92 suitably attached to the housing 16 and gear case 75 in position to support the drive rollers 86 and 87 in position to feed cordage 90. The cordage 90 fed by the rollers 86 and 87 is withdrawn from a supply (not shown) and passes over a guide pulley 93 (Figs. 1 and 2) journaled for free rotation on a bracket 94. The bracket 94, in addition to supporting the pulley 93, also supports a trigger mechanism designated by the numeral 95 and so positions the pulley 93 that cordage 90 fed over the pulley will be directed into a funnel-shaped guide member 96 having a pair of wings 97-97 as shown in Fig. 1, for guarding the upper surface of the feed rollers 86 and 87. The guide member 96 is cut away as shown at 98 (Fig. 2) to permit the entry therein of a trigger 99. The left end (Fig. 2) of the trigger 99 is bifurcated to receive the cordage 90 between its tines and is pivoted on a pivot pin 100 and urged to rock clockwise to the position shown in Fig. 2 by a spring pressed plunger 101 seated in a socket 102 formed in the bracket 94 and urged to the left (Fig. 2) by a compression spring 103. Movement of the trigger 99 clockwise beyond the position in Fig. 2 is blocked by a surface of the housing of a switch 104.

As is shown most clearly in Fig. 1, the cordage 90 has conductors 105-105 thrown out through its covering at intervals and when a group of

these extending conductors engage the trigger 99 they will rock the trigger counter-clockwise against the action of the spring 103 thus to actuate the switch 104. As shown most clearly in Fig. 6 the switch 104 has an actuator plunger 106, which upon movement of the trigger 99 in a counter-clockwise direction (Fig. 2) will shift a contact member 107 into engagement with a contact 108. The contact member 107 is normally urged to an inoperative position (opposite to that shown in Fig. 6) by a spring 109 and will be locked in its operated position by an armature 110 of a relay 111, a camming projection 112 on the armature 110 serving to hold the contact member 107 in its operated position until the relay 111 is energized. The contact member 107 upon engaging the contact 108 will complete a circuit from a current source 113 to energize the solenoid coils 40 and 42, and will hold the solenoid coils energized until the relay 111 is operated under control of a switch 114.

The worm gear 80 on the shaft 78 meshes with a worm gear 120 which is mounted upon a nozzle member 121 by means of a locking ring 122. The nozzle member 121 is freely rotatable in bearings 123 which are held in the housing 16 by a retainer ring 124 and which cooperate with an upper bearing member 125 to position the nozzle member 121 in the path of cordage 90 fed downwardly by the feed rollers 86 and 87. Operation of the feed rollers 86 and 87 and the nozzle member 121 will be initiated each time a switch actuator 126 mounted upon the cord coil supporting table 13 passes the switch 114 due to the engagement of the switch actuator 126 with a plunger 127 of the switch 114.

In the operation of the apparatus cordage 90 may be withdrawn from a suitable supply (not shown) and directed over the guide pulley 93 and thence down between the feed rollers 86 and 87 and through the nozzle member 121 to prepare the apparatus for operation. As soon as current is supplied to the motor 17 the feed rollers 86 and 87 will feed the cordage downwardly into the nozzle member 121 due to the fact that with the circuit in the condition shown in Fig. 6 the solenoid coil 40 is de-energized. The cordage drawn over the pulley 93 by the feed rollers 86 and 87 will continue to feed through the nozzle member 121 which will be rotated through the gearing including the worm gears 80 and 120 at all times that the feed rollers 86 and 87 are driven. Since the motor 17 operates continuously, the feeding of cordage will continue until solenoid 42 is energized to release the clutch discs 24 and to permit spring 38 to apply pressure to the brake discs 33. The shaft 23 will therefore continue to be driven, and, through the gearing in the gear case 75 will continue to drive the feed rollers 86 and 87 until looped out conductors 105 of the cordage 90 engage the trigger 99 thus to operate switch 104. When switch 104 is operated to engage contact member 107 with contact 108 it will be locked in its operated position by the armature 110 and due to the completion of a circuit through the contacts of switch 104 the solenoid coils 40 and 42 will be energized. Energization of the coil 40 will render the clutch discs 24 ineffective and will render the brake discs 33 effective thus to stop rotation of the shaft 23 and stop the operation of the feed rollers 86 and 87 and nozzle member 21. Simultaneously with the stopping of the feeding of cordage, solenoid 42 will be operated to attract its core member 43 and 75 through the link 44 to rock the bell crank lever

45 counter-clockwise (Fig. 1). When the lever 45 is rocked counter-clockwise the plunger 48 will be moved to the left (Figs. 1 and 4) and through the operation of the double sided rack 49 will rotate the shafts 55 and 56 in opposite directions to swing the closure plates 60 and 61 out from under the wall member 63, that is, from the position shown in full lines in Fig. 2 to the position shown in dot and dash lines, thus to drop the coil of cordage 90 which had been in the coil receptacle 62 into the cord coil supporting table 13. The apparatus will remain in the condition where the closure plates are open and the feed rollers 86 and 87 and nozzle member 121 are inoperative until the table 13 carries a switch actuator 126 into engagement with the plunger 127 whereupon switch 114 will be operated to supply current to relay 111 and thus attract armature 110 and release contact member 107. When the contact member 107 is released, the spring 109 will retract it to the position shown in Fig. 6 and the circuit to the solenoid coils 40 and 42 will be broken, thus to reinitiate a feeding cycle for the cordage. When the solenoid coil 40 is de-energized the shaft 36 will be swung to its clockwise position (Fig. 3) by the contractile spring 38, thus to apply pressure to the clutch discs 24 and interconnect the motor 17 and the shaft 23. De-energization of the solenoid coil 42 will permit the spring 50 to return the plunger 48 to its normal position thus moving the closure plates 60 and 61 back under the coil receptacle 62 in position to receive the cordage laid into the coil receptacle by the nozzle member 121. The cordage 90 will extend through the bottom of the receptacle 62 being clamped by the gaskets 65 on the abutting faces of the closure members 60 and 61, and thus as the table 13 continues its rotation some cordage may be withdrawn from the previously formed coil laying on the table 13 during the formation of a succeeding coil in the receptacle 62.

What is claimed is:

1. An apparatus for delivering coils of cordage to a processing machine comprising means for withdrawing cordage from a supply thereof, means for coiling the cordage withdrawn from the supply, means associated with the coiling means for receiving the coils, and means under control of the cordage for causing the receiving means to discharge a coil onto the processing machine.

2. An apparatus for delivering coils of cordage to a processing machine comprising means for withdrawing cordage from a supply thereof, means for coiling the cordage withdrawn from the supply, means having a movable bottom for receiving the coils from the coiling means, and means under control of the cordage for moving said bottom to discharge a coil from the coil receiving means.

3. An apparatus for delivering coils of cordage to a processing machine comprising means for withdrawing cordage from a supply thereof, means for coiling the cordage withdrawn from the supply, means associated with the coiling means for receiving the coils, means under control of the cordage for causing the receiving means to discharge a coil onto the processing machine, and means under control of the processing machine for initiating operation of the coiling means.

4. An apparatus for delivering coils of cordage to a processing machine comprising means for withdrawing cordage from a supply thereof, means for coiling the cordage withdrawn from the

supply, means associated with the coiling means for receiving the coils, means under control of the cordage for causing the receiving means to discharge a coil onto the processing machine, and means under control of the processing machine for restoring the receiving means to condition to receive a coil.

5. An apparatus for forming coils in a continuous length of flexible material comprising a coil supporting table, a coil receptacle positioned to discharge a coil onto said table, a coiling nozzle for forming a coil in said receptacle, means for feeding material to said coiling nozzle, and means controlled by the material for interrupting operation of the material feeding means and the coiling nozzle.

6. An apparatus for forming coils in a continuous length of flexible material comprising a coil supporting table, a coil receptacle positioned to discharge a coil onto said table, a coiling nozzle for forming a coil in said receptacle, means for feeding material to said coiling nozzle, means controlled by the material for interrupting operation of the material feeding means and the coiling nozzle, and means on the coil supporting table for initiating operation of the feeding means and coiling nozzle.

7. An apparatus for forming coils in a continuous length of flexible material comprising a coil supporting table, a coil receptacle positioned to discharge a coil onto said table, a coiling nozzle extending into said receptacle and operative to lay a coil of material in said receptacle, means for feeding material to said coiling nozzle, and means controlled by the material for interrupting operation of the material feeding means and coiling nozzle.

8. An apparatus for forming coils in a continuous length of flexible material comprising a movable coil supporting table, a coil receptacle positioned adjacent the path of movement of said table to discharge coils onto said table, means cooperating with said receptacle to lay material in a coil in the receptacle, means controlled by the material for interrupting operation of the coil forming means, and means on said table for intermittently initiating operation of the means cooperating with the receptacle to lay a coil therein.

9. A device for coiling multi-conductor cords having the conductors projecting in loops therefrom at regular intervals which comprises a receptacle having a movable bottom therein, an angularly disposed nozzle positioned to direct cordage into said receptacle, means for rotating the nozzle to lay the cordage in a coil on the bottom of the receptacle, means for feeding cordage to said nozzle, and a trigger positioned to be engaged by the loops of conductors for causing the bottom of the receptacle to be withdrawn when a predetermined length of cordage has been coiled therein.

10. An apparatus for forming coils in multi-conductor cordage having the conductors extending from the cordage in loops at intervals comprising a receptacle having a movable bottom, a nozzle rotatably movable with respect to said receptacle to lay a coil of cordage therein, means for feeding cordage to the nozzle, and means positioned to be engaged and operated by the loops of conductors as the cordage is fed by the feeding means for controlling the operation of the movable bottom, feeding means and nozzle.

11. An apparatus for forming coils in multi-conductor cordage having the conductors extend-

ing from the cordage in loops at intervals comprising a receptacle having a movable bottom, a nozzle rotatably movable with respect to said receptacle to lay a coil of cordage therein, means for feeding cordage to the nozzle, a common driving means for the nozzle and feeding means, and means operated by a loop extending from the cordage for interrupting operation of the driving means.

12. An apparatus for forming coils in multi-conductor cordage having the conductors extending in loops from the cordage at intervals comprising a receptacle, a nozzle rotatable with respect to the receptacle to coil cordage therein, means for feeding cordage to the nozzle, means cooperating with said receptacle to discharge a coil from the receptacle, a trigger positioned to be actuated by the loops extending from the cordage, and means under control of the trigger for interrupting operation of the feeding means and nozzle and for initiating operation of the discharging means.

13. An apparatus for forming coils in multi-conductor cordage having the conductors extending in loops from the cordage at intervals comprising a receptacle, a nozzle rotatable with respect to the receptacle to coil cordage therein, means for feeding cordage to the nozzle, means cooperating with said receptacle to discharge a coil from the receptacle, a trigger positioned to be actuated by the loops extending from the cord-

age, means under control of the trigger for interrupting operation of the feeding means and nozzle and for initiating operation of the discharging means, a control circuit operable under control of said trigger to effect the interruption of operation of the feeding means and nozzle, and means associated with said control circuit for intermittently initiating operation of said feeding means and nozzle.

14. An apparatus for forming coils in multi-conductor cordage having the conductors extending in loops from the cordage at intervals comprising a receptacle, a nozzle rotatable with respect to the receptacle to coil cordage therein, means for feeding cordage to the nozzle, means cooperating with said receptacle to discharge a coil from the receptacle, a trigger positioned to be actuated by the loops extending from the cordage, and means under control of the trigger for interrupting operation of the feeding means and nozzle and for initiating operation of the discharging means, a control circuit operable under control of said trigger to effect the interruption of operation of the feeding means and nozzle, and means associated with said control circuit for intermittently initiating operation of said feeding means and nozzle, said control circuit also including means for restoring the discharging means to unoperated condition.
